UNITED STATES PATENT OFFICE.

EUGENE E. HOFFMAN, OF CORAOPOLIS, PENNSYLVANIA, ASSIGNOR TO CONSOLIDATED LAMP AND GLASS COMPANY, OF CORAOPOLIS, PENNSYLVANIA, A CORPORATION OF WEST VIRGINIA.

LIGHTING-FIXTURE.

1,210,315.

Specification of Letters Patent. Patented Dec. 26, 1916.

Application filed June 22, 1916. Serial No. 105,225.

To all whom it may concern:

Be it known that I, EUGENE E. HOFFMAN, a citizen of the United States, residing at Coraopolis, in the county of Allegheny and 5 State of Pennsylvania, have invented certain new and useful Improvements in Lighting-Fixtures; and I do hereby declare the following to be a full, clear, and exact description of the invention, such as will enable others skilled in the art to which it 10 appertains to make and use the same.

This invention relates to illuminating and lighting fixtures generally, but is designed and intended more especially for use as a 15 ceiling fixture or bowl.

It has for an object the production of an exceedingly attractive and highly ornamental fixture of the character indicated, which is comparatively inexpensive to manufacture, also of simple construction, and as a consequence easily assembled, or dismantled by either skilled or unskilled persons for purposes of cleaning, repairing, or 20 for replacing lamps therein.

25 A further object is the production of fixtures wherein the glass-ware or shade element is formed of independent separable sections, thereby facilitating repairs in case of breakage by the mere substitution of 30 parts.

A further object of the invention is the provision of means for insuring a most efficient distribution of light, and the reflection thereof in a downward direction.

35 A further object is the production of a light, durable and compact fixture wherein the several coöperating parts are assembled and combined in a novel and peculiarly effective manner.

40 With the foregoing and other objects and advantages in view the invention will be hereinafter particularly described and later pointed out in the appended claims.

In the accompanying drawings which 45 form part of this application for Letters Patent, and whereon corresponding numerals refer to like parts in the several views: Figure 1, is a side elevation of the invention the several component parts thereof being here shown in assembled and operative relation, Fig. 2, is a vertical central section upon a relatively enlarged scale, taken through the complete device showing its structural arrangement, and Fig. 3, is a

horizontal section taken upon the line 3—3 55 of Fig. 2, looking downward, but on a scale corresponding with that of Fig. 1.

Although the drawings illustrate the present invention in connection with incandescent electric lamps, it will, of course, be 60 understood that any other source of light may be employed, and that the form or character of burner or illuminating device may be varied indefinitely without in the least departing from the spirit of my invention. 65

Reference being had to the drawings which illustrate the preferred form of construction, and to the numerals thereon, 1 indicates a ceiling and 2 a tubular outlet 70 therefrom, threaded upon its lower end as at 3. Surrounding said tubular outlet 2, for electric wires 4 which communicate with a suitable generator (not shown), is a reflector 5 of any suitable material and configuration, that of the present illustrations 75 being of silvered glass, convex in form, and circular in its outside dimensions.

Upon the threaded lower end 3 of outlet 2, immediately beneath reflector 5, is screwed 80 a follower or union coupling 6, having a plurality of horizontally arranged laterals 7 radiating therefrom, at a point intermediate its ends, and in turn themselves screw threaded upon their interiors. Into 85 these laterals 7 are secured hollow wire conducting stems 8 upon which are mounted horizontal lamps 9 in the well understood manner, and likewise into the lowermost end of outlet 2 is received another stem 10 90 for similarly supporting a depending lamp 11 and wiring connections as shown by Fig. 2.

Immediately beneath the coupling 6, and upon the projecting end of tubular outlet 2, 95 is screwed the hub 12 of a circular flanged cap 13 threaded upon its interior as at 14, one function thereof being to securely follow up, and retain in position, the superimposed coupling 6, and reflector 5 afore- 100 said.

Surrounding reflector 5, and practically inclosing all parts heretofore mentioned, is a main shade member or section 15 of transparent or translucent material and of convex form, having a central opening 16 of liberal proportions. The form of convex shade member 15 shown is practically that 105

of a hemisphere with its central portion upwardly indented around opening 16. As best shown by Fig. 2 the said convex shade member 15, or the annular indented portion 17 thereof, is supported directly upon the circular shoulder 18 of a depending secondary shade member 19, also of transparent or translucent material such as glass, the present illustrations showing this element as of substantially acorn form, and in any event provided with an upwardly extending neck 20 having a threaded exterior 21. This threaded exterior 21 of neck 20 upon member 19, is a counterpart of thread 14 upon the interior of flange 13, and is screwed thereinto when the fixture is assembled, for the double purpose of supporting the secondary shade member 19, and by agency of the latter similarly supporting the main shade member 15, beneath ceiling 1. And by reason of the extended lower end of tubular outlet 2 it will be observed that a range of adjustment is provided to accommodate shades of varying depths and shape.

Obviously the shade members 15 and 19, may be plain as shown, or the surface configuration and ornamentation thereof may be varied indefinitely without departing from the invention involved. They may be of clear glass or colored, of cut glass or molded, prismatic, corrugated or otherwise decorated, in manner and form as is well understood by persons skilled in the art to which this invention relates. In any event, however, it is desirable, although by no means essential, that shades of this character be ground, etched, sandblasted or otherwise frosted upon one or both surfaces as a means of softening or diffusing the light rays.

This being a description of the present invention its use and operation are quite obvious and need not therefore be herein dwelt upon. It may be noted however, with what facility the secondary shade member 19 follows up all other parts of the structure and keys them securely and adjustably together; and it should also be noted that it is considered quite within the spirit of my invention to finally secure this shade member 19 into its flanged cap 13, either by screw threads as shown, or any other suitable means which is readily detachable.

Having thus described my invention, what I now claim and desire to secure by Letters Patent is:

1. A lighting fixture including in combination a suitable hanger, a shade section depending from said hanger, a second shade section resting upon and supported by the first mentioned section, and a reflector positioned within the second shade section aforesaid.

2. A lighting fixture including in combination a vertically adjustable hanger hav-

ing depending flanges, a shade section detachably secured to the flanges of said hanger and an independent shade section having a central opening adapted to receive the upper portion of the first mentioned shade section and to rest thereon.

3. A lighting fixture including in combination a suitable hanger adapted for screw threaded connection with a fixed support, a vertically adjustable central shade member carried by said hanger, and an independent shade member surmounting the first mentioned shade member and with it adjustable vertically by agency of the screw threaded connection aforesaid.

4. A lighting fixture including in combination a suitable hanger adapted for screw threaded connection with a fixed support, a vertically adjustable central shade member carried by said hanger, an independent shade member superimposed in concentric relation with the first mentioned shade member and with it adjustable vertically by agency of the screw threaded connection aforesaid.

5. A lighting fixture including in combination a suitable hanger adapted for screw threaded connection with a fixed support, a vertically adjustable central shade member carried by said hanger, an independent shade member having a central opening supported upon the first mentioned shade member and with it adjustable vertically by agency of the screw threaded connection aforesaid.

6. A lighting fixture including in combination a suitable hanger adapted for screw threaded connection with a fixed support, a vertically adjustable lower shade member of globular form carried by said hanger, an independent inverted shade member having a central opening supported upon the first mentioned shade member and with it adjustable vertically by agency of the screw threaded connection aforesaid.

7. A lighting fixture including in combination a suitable hanger adapted for screw threaded connection with a fixed support, a vertically adjustable lower shade member of globular form depending from said hanger, an independent inverted shade member having a central depression and opening supported upon the first mentioned shade member and with it adjustable vertically by agency of the screw threaded connection aforesaid.

8. A lighting fixture including in combination a suitable hanger, a depending shade section having a constricted neck portion detachably secured to said hanger, and an inverted bowl-shaped shade section having a central opening adapted to receive the upper portion of the first mentioned shade section and to rest thereon in a plane below that occupied by its said neck portion.

9. A lighting fixture including in combination a vertically adjustable hanger, a

shade section detachably secured to said hanger, a ceiling bowl having a central opening adapted to receive the upper portion of the first mentioned shade section and 5 to rest thereon whereby vertical adjustment of the hanger aforesaid forces the fixture into contact with a ceiling.

In testimony whereof I affix my signature, in presence of two subscribing witnesses.

EUGENE E. HOFFMAN.
